UNITED STATES PATENT OFFICE

MELVIN E. VANSICKLE, OF NEWARK, NEW JERSEY, ASSIGNOR TO BRANDES LABORATORIES, INC., OF NEWARK, NEW JERSEY, A CORPORATION OF NEW JERSEY

ELECTRICAL PHONOGRAPH APPARATUS

Application filed March 17, 1927. Serial No. 176,089.

My invention relates broadly to electrical phonograph pick-up devices and more particularly to an electromagnetic phonograph pick-up device.

5 One of the objects of my invention is to provide a construction of electrical phonograph pick-up device comprising a relatively small number of parts assembled in a compact manner for actuation by the stylus of 10 the phonograph for securing relatively large changes in the magnetic condition of an electromagnetic winding for controlling an electron tube amplification system at relatively large amplitude.

15 Another object of my invention is to provide a construction of electromagnetic actuator for electrical phonographs in which an armature member is mounted within an electromagnetic winding for actuation by the 20 stylus of a phonograph for effecting changes in the magnetic condition of the electromagnetic winding in accordance with a sound record.

25 Another object of my invention is to provide a construction of electrical phonograph pick-up device in which an armature member in the form of a pedestal is rockably mounted within an electromagnetic winding, the armature member being flanged intermediate 30 the ends thereof to allow the resilient setting of the armature within the casing of the pick-up device in a position in which vibrations from a stylus may be readily transferred to the armature.

35 Another object of my invention is to provide a construction of electrical phonograph pick-up device in which an armature member is caused to be rockably mounted within an electromagnetic winding and in co-operation 40 with a stylus in such manner that the armature member may be vibrated in either of two directions according as the stylus is required to follow vertically or laterally formed sound records.

45 Other and still further objects of my invention reside in the construction and arrangement of parts for the electrical phonograph pick-up as described in the following specification and illustrated in the accompanying drawings, in which:

Figure 1 is a side elevation of a phonograph showing the electrical pick-up of my invention in position on the phonograph; Fig. 2 is a longitudinal cross-sectional view taken through the electrical phonograph 55 pick-up; Fig. 3 is a cross-sectional view taken on line 3—3 of Fig. 2; Fig. 4 is a lateral cross-sectional view taken through the phonograph pick-up on line 4—4 of Fig. 3; Fig. 5 is a lateral cross-sectional view taken through the 60 electrical phonograph pick-up on line 5—5 of Fig. 3; Fig. 6 is a cross-sectional view taken through the electrical phonograph pick-up on line 6—6 of Fig. 2; Fig. 7 shows the arrangement of pole members by which the upper end 65 of the armature is controlled; and Fig. 8 is a side elevation of the armature member employed in the electrical phonograph pick-up of my invention.

Referring to the drawings in more detail, 70 reference character 1 illustrates the phonograph which is equipped with the electrical pick-up of my invention. Reference character 2 indicates the revolvable record table for the phonograph arranged to carry record 75 3 over which the arm 4 is arranged to swing. The electrical phonograph pick-up device is illustrated at 5 as comprising a supporting member 7 and socket member 6 which may fit into the end of the arm 4. A permanent magnet 8 is positioned with respect to the supporting member 7 by means of a clamping strip 9 and screw member 10. I provide a pair of pole pieces 11 and 12 between the poles of the permanent magnet 8, the pole 80 pieces terminating in arcuate shaped pole faces 34 and 35 on opposite sides of the armature member 19 and are secured in position by means of screw members 14 and 15 which extend through the supporting member 7. 85 A resilient pad 16 is positioned with respect to a spacer plate 17 and upper resilient pad 18 as represented in Fig. 3 and between the resilient pads 16 and 18 the armature member 19 is centered and resiliently supported, 90 the flange 20 thereof being gripped on its opposite faces by the resilient pads 18 and 16. The armature member 19 has one end thereof reduced and formed in polygonal cross section as represented at 21. A resilient sleeve 100

22 fits over the polygonal portion 21 of the armature 19 and forms an abutment for the pole pieces 23 and 24 which are adjustable upon the pole members 11 and 12 by means of screws 23a and 24a operating in slots 23b and 24b. The coil support 26 is mounted between the pole members 11 and 12 and the pole pieces 23 and 24. This coil support has a hollow core through which the armature 19 passes. An electromagnetic winding 25 is carried by the coil support 26 and is subjected to changes in its magnetic condition in accordance with vibrations of the armature member developed by movement imparted thereto from the stylus 30 which is mounted and secured in the socket member 29 by means of adjustable set screw 31.

It will thus be seen that the armature member 19 is adapted to be vibrated in either of two planes according as the stylus 30 is required to follow a vertically formed sound track or a laterally formed sound track of the sound record. The pole pieces 23 and 24 are so arranged with respect to the armature member 19 that the lines of magnetic flux will be varied in accordance with the vibration of the armature member irrespective of the plane in which the vibration is set up.

The entire assembly is housed within the cover portion 27 secured through the strip 9 by means of screw members 28 forming a dust proof casing for the phonograph pick-up. Conductors 36 lead from the electromagnetic winding 25 through the socket 6 to suitable contact members by which they may be plugged into cooperating sockets in the phonograph arm 4 for establishing connection with the electron tube amplification apparatus which may be positioned within the phonograph cabinet.

The electrical phonograph pick-up of my invention comprises a relatively small number of parts thereby facilitating manufacture and production and decreasing the manufacturing cost.

While I have described the invention in its preferred embodiment, I desire it to be understood that modifications may be made and that no limitations are intended other than are imposed by the scope of the appended claims.

What I claim as new and desire to secure by Letters Patent of the United States is as follows:

1. An electrical phonograph pick-up comprising a supporting member, a permanent magnet carried by said supporting member, a pair of pole pieces positioned between the poles of said permanent magnet, said pole pieces terminating in arcuate shaped pole faces directed toward each other, at one end and having pole faces cut on opposite angles at the opposite end thereof, an armature member resiliently mounted between said pole faces, said armature member being dis-

posed within an electromagnetic winding and having a circular cross-section throughout a portion of its length and a polygonal cross-section adjacent the end thereof, whereby said pole faces conform to the contour of said armature, and a stylus carried in the end of said armature member for transferring vibrations to said armature member and variably controlling the magnetic condition of said electromagnetic winding. 75

2. An electrical phonograph pick up comprising a supporting member, a permanent magnet carried by said supporting member, a pair of pole pieces positioned between the poles of said permanent magnet, said pole pieces terminating in arcuate shaped pole faces directed toward each other at one end and angularly formed pole faces at the opposite end, an electromagnetic winding positioned between said pole pieces, an armature member having an integral flange intermediate the ends thereof with a portion of its length circular in cross-section and a portion thereof polygonal in cross-section, whereby said pole faces closely conform to the contour of said armature, means secured to said supporting member for resiliently gripping opposite sides of said flange for positioning said armature member within said electromagnetic winding, a stylus carried in one end of said armature member for displacing said armature member within said electromagnetic winding and effecting a change in the magnetic condition thereof. 85

3. An electrical phonograph pick-up comprising a supporting member, a permanent magnet carried by said supporting member, a pair of pole members positioned between the poles of said permanent magnet, said pole members having arcuate shaped pole faces directed toward each other, a pair of adjustable pole faces secured to the opposite ends of said pole members, a cylindrical armature member having an integrally connected flange intermediate the ends thereof, 100 means for resiliently gripping opposite faces of said flange in a position adjacent said arcuate shaped pole faces, said armature member carrying a stylus at one end and projecting beyond said adjustable pole faces at 105 the opposite ends of said pole members, and an electromagnetic winding positioned between said pole members and said adjustable pole faces and concentrically positioned about said armature member whereby vibrations of said stylus in either of two planes angularly disposed to one another when imparted to said armature member will effect changes in the magnetic condition of said electromagnetic winding. 110

4. An electrical phonograph pick-up comprising a supporting member, a permanent magnet carried by said supporting member, a pair of pole members positioned between the poles of said permanent magnet, said pole 115

members terminating in arcuate shaped pole faces, a pair of adjustable pole faces positioned upon the opposite ends of said pole members, an electromagnetic winding located between said pole members, an armature member having a cylindrical body portion and an integrally connected cylindrical flange, means gripping opposite faces of said flange for rockably mounting said armature member between said pole faces and within said electromagnetic winding, one end of said armature member carrying a stylus and the opposite end of said armature member having a polygonal shape and being covered by a sleeve of resilient material arranged to be centered between correspondingly shaped pole faces of said adjustable pole members, whereby vibrations of said stylus in either of two planes angularly disposed to one another when imparted to said armature member will effect changes in the magnetic condition of said electromagnetic winding.

5. In a phonograph pick-up device having a magnetic circuit, the combination of, a pair 25 of pole pieces forming a part of said magnetic circuit, an armature disposed in a gap between said pole pieces and mounting means for said armature to allow movement thereof in said gap in directions to reproduce vertically and laterally cut records in the same position of the device relative to the records.

6. In a phonograph pick-up device having a magnetic circuit, the combination of, a pair 35 of pole pieces in said magnetic circuit forming two gaps therein, an armature passing through one of said gaps and having an end portion thereof disposed in the other of said gaps, said end portion having a substantially square cross section and each of said pole pieces being shaped to conform to two sides of said end portion, and means for mounting said armature to allow movement thereof in two directions relative to said pole pieces.

45 7. In a phonograph pick-up device having a magnetic circuit, the combination of, an armature forming a part of said magnetic circuit, mounting means to allow movement of said armature in two directions substantially perpendicular to each other, a pair of pole pieces forming another part of said magnetic circuit and a gap therein, an end portion of said armature disposed in said gap, and end portions of said pole pieces shaped 50 with respect to said armature end portion so that equal movements of said armature in said directions produce substantially equal changes of magnetic flux in said armature.

8. In a phonograph pick-up device having 60 an armature disposed in a gap between two poles of a magnetic circuit, means for mounting said armature to allow movement thereof in either of two directions relative to said poles, said directions being substantially perpendicular to each other and said pole pieces

having end portions thereof shaped to conform to the portion of said armature adjacent thereto so that equal movements of said armature in said directions cause substantially equal changes of magnetic flux in said armature.

In testimony whereof I affix my signature.

MELVIN E. VANSICKLE.
